APPARATUS FOR COLORING PHOTOGRAPHIC MOUNTS

Paul J. Stuparich, San Francisco, Calif.

Application June 5, 1933, Serial No. 674,412

2 Claims. (Cl. 41—29)

My invention relates to a new and useful apparatus for use in connection with a process for spraying a coloring compound for bordering photographic mounts and the like.

5 In the art of spraying and decorating photographic mounts, it has previously been found very difficult to properly spray coloring or tinting fluids upon the mount material, and to secure clearly defined border lines, that is, to successfully block out certain sections of the mount while other sections thereof are being sprayed and tinted.

10

The material in general use for this purpose is more or less spongy, and the surfaces to be sprayed are always more or less uneven, hence, the sprayed fluid tends to run or spread to some extent, thus tending to produce wavy or irregular border lines between different shades of sprayed fluid, or along border lines bordering openings, or marginal lines of the sprayed mounts.

The apparatus constituting the present invention tends to obviate these difficulties by the employment of a specially developed apparatus which not only effectively blocks out the areas 25 of the mounts to be left untouched by the spraying fluid, but also provides a means for the immediate absorption of any excess fluid by capillary action, which fluid may be sprayed upon the material without in any way affecting the perfection 30 of the definition of the border lines acquired in this manner.

The principal object of the invention is to provide a simple and efficient apparatus of the character disclosed, to enable the operator to effectively and quickly block out certain sections of the photographic mount while the spraying operation is carried on, so that the mount or mounts may be thoroughly and artistically decorated or tinted; and so that the finished mounts will have clearly and perfectly defined contrasting border lines.

40 and perfectly defined contrasting colors.
A further object of the invention is to provide an improved spraying apparatus which enables the operator to effectively spray large numbers of mounts with a minimum of labor and time, the finished mounts thus sprayed being perfect in color and border line definition.

A still further object of the invention is to so simplify the spraying operation and the number of parts of material utilized in producing the 50 mounts, that the cost of the same is kept at a minimum.

Other objects and advantages of the invention become apparent with reference to the subjoined specification and the accompanying two sheets of drawings in which:—

Figure 1 is a perspective view illustrating my improved method of mounting and blocking the mount while it is being sprayed by the use of the usual spraying apparatus;

Figure 2 is a transverse section taken through the base block, the mount and the apparatus utilized in conjunction with the spraying operation, said apparatus fitting into the base block as shown, and having its beveled edge overlapping the inner edges of the mount, to effectively block off a border surrounding the picture opening of the mount; the section being indicated by the section line 2-2 in Figure 1;

Figure 3 is a perspective view per se of the blocking and mount retaining unit;

Figure 4 is a side elevation illustrating a set of rolls for rolling and egg shelling the finished mount;

Figure 5 is a front elevation illustrating the finished and bordered mount section before it is applied to the foundation; and

Figure 6 is a front elevation illustrating the completed mount after it has been beveled and mounted on the foundation or backing.

In carrying out the process constituting the present invention, it is to be understood that it is the primary object to provide a simple yet very efficient method of producing an artistically designed photographic mount of exceptionally simple character and one that when properly sprayed, bordered and egg shelled, presents a most pleasing appearance due to the delicate colors employed and the sharpness of definition secured between the color work and the borders thereof. 80 85

The special process and apparatus employed in this art, consists of first providing blanks 10 of the proper size and texture, and punching the same to form the usual picture opening 11, as clearly disclosed in Figures 2, 5 and 6 of the drawings. 95

These blanks are then placed upon a base block 12 in which is provided an opening 13 of the same size as the openings 11—which openings are aligned for the reception of the blocking apparatus 14, Figures 1, 2 and 3. 10

This blocking apparatus embodies a depending section 15 made to fit snugly into the opening 13 in the base block 12, said section 15 being of metal and heavy enough to hold the apparatus in place in the base block. A plate 16 is secured to the upper face of the section 15 and is held securely thereon by means of screws 17, Figure 2, the outer overhanging edges being beveled to a knife edge 18 and resting upon the mount blank 10 in close proximity to the opening 11 formed

therein so that a border strip will be defined about the inner edges of the opening 11 when the product is completed.

A pad 19 of absorbent wicking material is provided and rests upon the plate 16, and a top clamp plate 20 rests upon said wicking, the whole being held securely together as a unit by means of a fixed bolt 21 having a knurled nut 22 mounted upon its upper threaded end, so that the wicking 19 may be removed and changed at will.

In Figure 1 the complete operation is shown, the blank 10 being illustrated as held in place by the blocking unit 14 with the spraying brush 23 in operation and spraying the liquid tinting material 24 upon the blank around the blocking unit.

The beveled section 18 of the plate 16 is held in close contact with the blank 10 due to the weight of the section 15, and this overhanging beveled section effectively seals a border section 25 entirely surrounding the picture opening 11 thus providing a perfect fully white border in contrast to the sprayed or tinted section 24 surrounding this border section.

The wick 19 due to capillary action, draws any excess fluid which may collect at the bevel edge 18 upwardly on said bevel, and absorbs the same so that when the apparatus is removed from the mount the sprayed material will not be smeared and the border will thus be perfectly defined.

After the blanks have been sprayed, they are inserted sprayed side up between a set of pressing rollers 26 and 27, together with a section of abrasive material 28 which produces a stippled egg shell effect, and at the same time removes any wrinkles which may remain in the finished blanks—the said finished blanks are then pasted at their upper edges 29 to suitable backing or foundation sheets 30 of a contrasting color.

I claim and desire to secure by Letters Patent of the United States the following:—

1. A device for use in spraying photographic mounts, said device including a plug adapted to enter into the opening in a mount, a plate provided with absorbent material and disposed upon said plug, said plate being of such size that it will overlap the edges of the said opening when said plug is entered therein, and means for clamping said plug and said plate together.

2. In a device for use in spraying photographic mounts, said device including a plug adapted to be seated in the opening in a mount, a plate disposed upon said plug and of such size that it will rest upon the edges of the opening in the mount and define a border therearound, said plate having a sharpened peripheral edge providing capillary means and absorbent material carried by said plate adjacent said peripheral edge.
